Albert F. Young
By his Attorney
Charles L. Wright.

UNITED STATES PATENT OFFICE.

ALBERT F. YOUNG, OF BROOKLYN, NEW YORK.

INVISIBLE SUSPENDERS.

1,342,704.

Specification of Letters Patent.

Patented June 8, 1920.

Application filed December 30, 1919. Serial No. 348,254.

To all whom it may concern:

Be it known that I, ALBERT F. YOUNG, a citizen of the United States, and a resident of Brooklyn, in the county of Kings and State of New York, have invented certain new and useful Improvements in Invisible Suspenders, of which the following is a specification.

This invention has as its principal object to provide a type of device used in supporting the lower garments, as worn by either sex, commonly known as a "pair of suspenders" or braces, in which the straps, bands, and other parts are disposed within the outer shirt and hence rendered invisible to ordinary observation.

A further object is to provide such suspenders in forms comfortable to wear, being self adjusting, easy to attach, efficient for their main purpose of support, additionally holding the overshirt relatively adjusted to the trousers, and finally providing a device that is neat in appearance and produced at low cost.

These objects are attained by the novel construction, combination and arrangement of parts, hereinafter described and shown in the accompanying drawings, forming a material part of this disclosure, and in which:—

Figure 1, is a perspective view showing the usual *ensemble* of garments, including the application of the invention and manner of attachment.

Fig. 2, is a fragmentary elevational view showing the connection between the back strap and the band.

Fig. 3, is a similar view, showing one form of connection between one of the front straps and the band.

Fig. 4, is a like view, showing a modification of the same.

Fig. 5, is an enlarged sectional view, taken on line 5—5 of Fig. 1, showing the parts as applied.

Fig. 6, is an enlarged front elevational view showing one form of strap support at the rear.

Fig. 7, is a fragmentary view showing the inner side of a trousers band as supplied with attaching means.

Fig. 8, is a similar view of the same, showing a modified attaching means.

Fig. 9, is a view similar to Fig. 6, showing a modified form of strap support.

Fig. 10, is a perspective view of a clip provided with attaching means.

Referring to the drawings in detail, the numeral 15 designates a lower garment, as a pair of trousers, the flap 16 being unbuttoned and turned down on one side, disclosing the usual buttons 17, attached in spaced relation to the inner side of the waist band 18, over which is secured loops 19, through which a belt may be passed, if the garment 60 is so supported, while ordinarily the buttons 17, are used to engage the ends of suspenders.

The outer shirt 20, is of the usual type, provided with sleeves 21, the parts of the 70 bosom meeting at the front 22, and finished with a collar band 23, as is customary, the undershirt 24, being disposed as common.

The article comprising the invention, as will be evident is worn between the outer 75 shirt 20, and the undershirt 24, and consists of an inelastic webbed strap 25, arranged to extend vertically at the center of the back from about the waist line to a point below the arms, at which point are secured two di- 80 verging branches 26, which pass over the shoulders to the front, in parallel straps 27, which have loops 28, at their lower ends secured adjustably by buckles 29.

Engaged in these loops are links 30, connecting sockets 32, formed by folding and uniting the ends of webbed material, and which support at their lower ends, other links 33, in turn engaging standard types of clasps or fasteners 34, engageable with buttons direct or over cloth, disposed about the buttons, in a well known manner.

Referring to Figs. 1 and 3, it will be seen that the sockets 32 are slotted lengthwise as at 36, while in Fig. 4, a metal clip 38, is 95 secured by stitches 39, to the face of the sockets, the slotted portions or clips serving to guide and support, as well as to frictional contact with an elastic belt 40, passing circumferentially around the body and secured 100 adjustably by the buckle 41.

The belt 40, also passes through a loop 42, fastened on the lower portions of the web strap 25, in such manner as to move freely up and down therein and is held relatively to 105 the strap by a short loop 43 attached to the belt.

The strap 25, is provided with a fixed button 45, secured immediately above the loop 42, and engageable therewith is a pad 46, 110

having a buttonhole 47, while diverging from the pad are a pair of short straps 48, carrying at their lower ends clasps 49, engageable with the buttons 17, at the rear 5 of the waist band, 18, the construction being shown in detail in Fig. 6.

A similar device, shown in Fig. 9, includes a pad 50, having a button hole 51, engageable with the button 45, and from which extends 10 a single strap 52, carrying at its lower end a fixed button 53, in turn engageable in a reversed position, a rigid clasp 54, sewn to the band 18, between the rear buttons 17.

These clasps, as shown in Fig. 10, are provided 15 with a plurality of pins 55, which are inserted through the waist band and bent over, forming a secure fastening means which is hidden below the belt loops 19, of the waist band or they may be attached by 20 stitching.

It will be noted that buttons 56, similar to the buttons 53, are shown secured to the inner side of the waist band, 18, between the fixed buttons 17 on the front sides of the garment, 25 thus providing a variety of points where attachments of the front straps can be made as may be preferred or more convenient, thus obviating attaching the suspenders at any one fixed point, and preventing undue wear 30 of the shirt by being able to shift from one button to another, distributing the wear more equally.

In operation the straps 25 and 27 are placed over the shoulders of the wearer, on 35 the undershirt, and the outer shirt 20, drawn over.

The trousers or other lower garments are then positioned and the clasps applied to the buttons, the intervening shirt material being 40 passed over the buttons so as to be held by the clasps, thereby preventing the shirt from raising, or the lower garment from dropping, the latter being held in any desired adjustment, as is also the elastic belt 40.

45 Thus the device can be worn with entire comfort, dispensing with the use of ordinary suspenders or braces and belts, and without being seen from the exterior of the garment.

From the foregoing it will be seen that the 50 suspenders can be used without any changes in the trousers buttons whatever, or if preferred, the additional buttons 56 may be supplied and the loop 54, thus presenting a three point support which is specially easy on the wearer and of exceptional neat appearance.

Having thus described my invention, and set forth the manner of its construction and application, what I claim as new and desire to secure by Letters Patent is:—

60 1. A device of the class described, comprising in combination, a single inelastic webbed strap reaching from the waist to a point approximately level with the shoulder, a pair of branches extending therefrom adapted 65 to pass over the shoulders, an elastic belt,

support clips at the lower portions of said branches through which said belt freely passes, an elongated loop on said strap engaging said belt permitting relative transverse movement, and means at the extremities of said branches and strap adapted to engage with a plurality of fasteners upon the lower garments selectively. 70

2. A device of the class described, comprising in combination, a relatively wide vertical strap at the back, a pair of diverging branches at the top thereof, said branches being adapted to extend over the shoulders downwardly at the front, an elongated loop secured near the bottom of said strap, an elastic belt loosely engaged in said loop movable up and down therein, means on said belt preventing longitudinal movement of said belt through said loop, support clips on the bottom of said branches through which 85 said belt passes, and clasps carried at the ends of said strap and said branches. 95

3. A device of the class described, comprising in combination, a back strap, branches extending therefrom over the shoulders and downward at the front, a flexible belt, connections between said strap and belt, said connections confining the movement of said belt in one direction and limiting its movement in another direction, other connections between said belt and said branches permitting lateral movement of the branches, clasps at the ends of said branches engageable with buttons at various points on the supported garment, and securing means removably engaged with said strap engageable with buttons at the rear of the garment. 100

4. A device of the class described, comprising in combination, a back strap, branches extending therefrom over the shoulders and downward at the front, a flexible belt, support connections between said belt, back strap and branches, said latter connections permitting the belt to pass freely therethrough, clasps carried by said branches, and interchangeable supporting means removably engaged with the bottom of said strap said means being adapted to engage at one or more points with the supported garment. 110

5. A device of the class described, comprising in combination, a back strap, a pair of narrow branches extending therefrom over the shoulders and at the front, a belt, connections between said belt and said strap permitting lateral movement of the belt, 115 other connections between said belt and said branches, permitting lateral movement of the branches, clasps at the ends of said branches, a button on said back strap, a pad engageable therewith, one or more branch 120 straps extending from said pad, and clasps carried at the ends of the last named straps. 125

In testimony whereof I have signed my name to this specification.

ALBERT F. YOUNG.
